UNITED STATES PATENT OFFICE.

EDWIN C. MADDEN, OF ST. LOUIS, MISSOURI.

SAFETY-RAZOR.

1,022,429.

Specification of Letters Patent.

Patented Apr. 9, 1912.

Application filed July 29, 1910. Serial No. 574,542.

To all whom it may concern:

Be it known that I, EDWIN C. MADDEN, a citizen of the United States, residing at St. Louis, Missouri, have invented a certain 5 new and useful Improvement in Safety-Razors, of which the following is a full, clear, and exact description, such as will enable others skilled in the art to which it appertains to make and use the same.

10 This invention relates to safety razors of the "hoe" type, namely, razors which comprise a comparatively short blade and comb or guard arranged at an approximately right angle to and adjacent the upper end 15 of a handle which the user holds in his hand during the operation of shaving so as to draw the blade downwardly over the surface being shaved. All of the various safety razors of this type which are now in general 20 use are intended to be operated by a downward stroke, and if the user desires to shave "up" or in an opposite direction to that in which the hairs of the beard normally project from the face, he has to invert 25 the handle or turn it upside down and then draw the blade upwardly across the beard. It is extremely awkward to shave with a 30 safety razor of the hoe type that is held in an inverted position, and moreover, it is difficult to accurately control the razor 35 when held in this manner so that the majority of users of safety razors of this type merely draw the blade downwardly over the face even though they do not obtain as close a shave as could be obtained by moving the 40 blade upwardly or against the beard.

The main object of my invention is to provide a safety razor of the type referred 45 to which is so designed that the cutting edge can be moved upwardly or against the beard without inverting the razor or turning the handle upside down, thereby permitting the razor to be held conveniently and controlled accurately during the operation 50 of shaving close to the skin.

Another object is to provide a safety razor of the hoe type which is so designed that it can be stroked upwardly and downwardly without materially changing the position of the handle.

Another object is to provide a safety razor of the type referred to having two cutting edges and combs or guards co-operating with said cutting edges and disposed

in such a manner that one cutting edge and 55 comb can be used during the operation of shaving upwardly or against the beard and the other cutting edge and comb used during the operation of shaving downwardly or with the beard without inverting the 60 handle of the razor or changing it from the position in which the handle of the safety razor is usually held.

Another object is to provide a substantially hoe-shaped safety razor having a 65 cutting blade which can be adjusted into different positions so as to enable the user to push the blade upwardly or draw it downwardly during the shaving operation without inverting the handle of the razor. 70

Other objects and desirable features of my invention will be hereinafter pointed out.

It is immaterial so far as my broad idea is concerned whether the razor is provided 75 with a single cutting edge that can be adjusted in different positions or two separate and distinct cutting edges, one of which is used to shave upwardly or against the beard and the other downwardly or with the 80 beard, and if the razor is provided with two separate and distinct cutting edges it is immaterial whether these edges are both formed on a single blade or on separate 85 blades. The blade or blades of the razor can either be rigid or they can be flexible or of the "wafer" type, and the particular means which is employed for supporting the blade or blades and retaining them in operative position is also immaterial so far as my 90 broad idea is concerned.

Figure 1 of the drawings is a side elevational view, partly in section, of a safety razor constructed in accordance with my invention, and provided with a flexible or 95 wafer blade having two separate and distinct cutting edges; Fig. 2 illustrates the way in which the razor is held during the operation of shaving upwardly, or against the beard; Fig. 3 illustrates the way in 100 which the razor is held during the operation of shaving downwardly or with the beard; Fig. 4 is a side elevational view of a razor embodying my invention and provided with two separate and distinct rigid 105 blades; Fig. 5 is a side elevational view of a razor embodying my invention and provided with a rigid blade having two sepa-

rate cutting edges; Fig. 6 is a front elevational view of a razor embodying my invention and provided with a single cutting blade that can be adjusted in different positions so as to enable the user to stroke the razor upwardly or downwardly without inverting the handle; Fig. 7 is a view of the razor shown in Fig. 6, and illustrates the way in which the blade of the razor is adjusted; Fig. 8 is a detail sectional view of the means used in the razor shown in Fig. 6 for retaining the blade in adjusted position; Fig. 9 is a front elevational view of an adjustable blade razor of the type shown in Fig. 6 but of a slightly different construction; and Fig. 10 illustrates the manner of adjusting the razor shown in Fig. 9.

Referring to Fig. 1 of the drawings, A designates the handle of a razor, and 1 designates a supporting plate on the upper end of said handle which carries a flexible blade B formed from a thin piece of steel and provided with a cutting edge 2 that is used during the operation of stroking the razor downwardly or with the beard and a cutting edge 3 that is used during the operation of stroking the razor upwardly or against the beard, said blade-supporting plate 1 having a downwardly inclined portion which terminates adjacent the cutting edge 2 and an upwardly inclined portion which terminates adjacent the cutting edge 3. The blade-supporting plate 1 is provided with guides 4 which pass through openings in the blade, and a cap 5 is arranged over the blade for clamping it to the support 1, the under side of said cap conforming to the top surface of the blade-supporting plate 1 so as to place the blade in tension and securely clamp it in position on said supporting plate. The clamping cap 5 is retained in position by means of a nut 6 mounted on a screw-threaded extension 6^a of the handle A. A comb or guard 2^a is arranged below the cutting edge 2 of the blade and a similar comb or guard 3^a is arranged above the cutting edge 3 of the blade, said combs operating to prevent the cutting edges of the razor from cutting the cuticle during the shaving operation. Any other suitable means than that herein shown, however, could be used for retaining the blade in position, and while I have herein shown the comb 2^a formed integral with the downwardly inclined portion of the blade-supporting plate 1 and the comb 3^a formed integral with the upwardly inclined portion of the clamping cap 5, I do not wish it to be understood that my invention is limited to this exact construction for the combs could be formed in various other ways without departing from the spirit of my invention.

During the operation of shaving downwardly the handle A is held in approxi-

mately the position shown in Fig. 3 or at an angle which will produce the best results so as to cause the cutting edge 2 to remove the beard when the handle is stroked downwardly, and when it is desired to shave upwardly or against the beard the handle A is twisted or turned so as to arrange the cutting edge 3 in operative position, as shown in Fig. 2, the handle A being thereafter moved upwardly so as to cause the cutting edge 3 to travel upwardly over the surface being shaved.

From the foregoing it will be seen that with my improved safety razor the user does not have to invert the razor or turn the handle upside down when he desires to shave upwardly or against the beard, and as the handle of the razor is held in substantially the same position for shaving upwardly and downwardly, the razor can be controlled more accurately than is possible with the safety razors now in general use.

Instead of providing the razor with a flexible blade, as shown in Fig. 1, the razor can be provided with two separate and distinct rigid blades B¹ and B² which are held in operative position on the rigid blade-supporting plate 1 by means of a clamping cap 5, said plate and cap being provided with upwardly inclined portions and downwardly inclined portions which carry the combs 2^a and 3^a that prevent the edges of the blades B² and B¹, respectively, from cutting into the cuticle. The exact inclination of the inclined portions of the blade-supporting plate 1 and clamping cap 5 are immaterial and can be modified to meet various conditions or requirements.

The razor illustrated in Fig. 5 is provided with a rigid blade B³ having a cutting edge 2 that is used during the operation of shaving downwardly, and a cutting edge 3 that is used during the operation of shaving upwardly, said blade being clamped in operative position on the blade-supporting plate 1 by means of the cap 5. The plate 1 can either be rigidly connected to the handle A, or, if desired, said plate can be connected to the handle by a knuckle-joint 7 of any preferred type so as to enable the blade to be adjusted at different angles with relation to the handle.

In Fig. 6 I have illustrated a razor embodying my invention which is provided with an adjustable blade B⁴ having a single cutting edge 8. Said blade is clamped in operative position on a supporting plate 9 by means of a cap 10, and said plate 9 is provided with a shaft 11 which is journaled in bearings 12 on a yoke 13 arranged at the upper end of the handle of the razor. The side arms 13^a of said yoke are preferably formed of spring material and are provided with pairs of projections 14 which fit in

notches formed in devices 15 connected to the shaft 11 so as to retain the blade either in the position shown in full lines in Fig. 7 so as to enable it to be used for shaving 5 downwardly or in the position shown in broken lines in Fig. 7 so as to enable it to be used for shaving upwardly. By pressing the arms 13^a of the yoke inwardly or toward each other the projections 14 on said arms 10 will be withdrawn from the coöperating recesses in the devices 15, thereby releasing the shaft 11 and permitting it to be adjusted in the desired position. The blade-supporting plate 9 is provided with a comb or guard 15 9^a which lies under the blade when said plate is adjusted in the position shown in full lines in Fig. 7 and thus prevents the blade from cutting into the cuticle during the operation of shaving downwardly. When the 20 plate 9 is adjusted in the position shown in broken lines in Fig. 7, namely, when the razor is being used to shave upwardly, the guard 9^a will lie above the blade and consequently it will travel in advance of the blade 25 and prevent the edge of same from cutting into the cuticle.

The razor illustrated in Figs. 9 and 10 is similar to the one illustrated in Figs. 6 and 7 in that it comprises a rigid blade B⁵ having a single cutting edge and arranged between clamping members 9' and 10' but instead of journaling the shaft 11^a of the blade-supporting plate in the arms of the yoke said shaft is loosely mounted in a bearing 16 on the upper end of the handle A said bearing being provided with a set screw 17 that is adapted to engage said shaft and thus lock the blade in adjusted position.

With a razor of the type shown in Fig. 6 40 or in Fig. 9 the blade is adjusted in the manner illustrated in full lines in Figs. 7 and 10 when it is desired to shave downwardly, and when it is desired to shave upwardly or against the beard the blade is adjusted in the 45 position shown in broken lines in Figs. 7 and 10, the user holding the handle A in approximately the same position with either adjustment of the blade.

Having thus described my invention, what 50 I claim as new and desire to secure by Letters Patent is:

1. In a safety razor, a handle, an upwardly inclined blade arranged adjacent the upper end of the handle, and a guard arranged on the upper side of the blade in such a manner that it travels in advance of the cutting edge of the blade during the operation of moving the blade upwardly over the surface being shaved.
2. In a safety razor, a handle, a transversely disposed blade-supporting member arranged adjacent the upper end of the handle and provided with an upwardly inclined portion, a blade mounted on the upwardly

inclined portion of said member, and a 65 guard arranged on the upper side of the blade for protecting the surface being shaved during the operation of moving the blade upwardly over said surface.

3. In a safety razor, a handle, a transversely disposed supporting member arranged adjacent the upper end of the handle and having upwardly and downwardly inclined portions, cutting edges arranged adjacent the ends of said inclined portions, a 70 guard arranged above the cutting edge that is located adjacent the end of the upwardly inclined portion of said member, and a guard arranged below the cutting edge that is located adjacent the end of the downwardly inclined portion of said member.

4. In a safety razor, a handle, a cutting means arranged adjacent the upper end of said handle and comprising upwardly and downwardly inclined portions provided 85 with cutting edges, a guard arranged above the upwardly inclined portion of said means in such a manner that it travels in advance of the cutting edge thereon, and a guard arranged below the downwardly inclined portion 90 of said means adjacent the cutting edge thereon.

5. In a safety razor, a handle, a transversely disposed supporting member arranged adjacent the upper end of said handle and having upwardly and downwardly inclined portions, a double-edged cutting means carried by said member, a clamping device for retaining said cutting means in position, a guard on said device arranged 95 above one of the cutting edges on said means, and a guard on said supporting member arranged below the other cutting edge on said means.

6. A safety razor, comprising a handle, 105 upwardly inclined clamping members arranged adjacent the upper end of said handle, a blade interposed between said members and provided with a cutting edge which is adapted to be used to shave upwardly 110 without inverting said handle, and a guard on the top clamping member arranged above the blade so that it travels in advance of the blade.

7. A safety razor, comprising a handle, a 115 blade supporting plate on said handle provided with an upwardly inclined portion and a downwardly inclined portion, a double-edged blade on said plate, a cap which clamps said blade in position, a guard 120 on said cap arranged adjacent one edge of said blade, and a guard on said plate arranged adjacent the other edge of said blade.

8. A safety razor, comprising a handle, a 125 stationary blade-supporting plate on said handle provided with an upwardly inclined portion and a downwardly inclined portion,

a clamping cap that conforms to the upper face of said plate, a double-edged flexible blade interposed between said cap and plate, a guard arranged above said blade adjacent one edge thereof, and a guard arranged below said blade adjacent the other edge thereof.

In testimony whereof I hereunto affix my signature in the presence of two witnesses, this twenty-seventh day of July 1910.
